(57) **CLAIM**

The ornamental design for a batter's hand guard, as shown and described.

DESCRIPTION

FIG. 1 is a front perspective view of a hand guard being worn by a baseball player;

FIG. 2 is a front, end perspective view of the hand guard of FIG. 1;

FIG. 3 is a back, side perspective view of the hand guard of FIG. 1;

FIG. 4 is a front view of the hand guard of FIG. 1;

FIG. 5 is a rear view of the hand guard of FIG. 1;

FIG. 6 is a first side view of the hand guard of FIG. 1;

FIG. 7 is a second side view of the hand guard of FIG. 1;

FIG. 8 is a top view of the hand guard of FIG. 1; and,

FIG. 9 is a bottom view of the hand guard of FIG. 1.

The dashed lines shown in FIGS. 1 through 9 illustrate environmental elements only and form no part of the claimed design.

1 Claim, 6 Drawing Sheets
